CLAIM

The ornamental design for a stapler, as shown and described.

DESCRIPTION

FIG. 1 is a front side view of the stapler design.

FIG. 2 is a rear view of the stapler design.

FIG. 3 is a right side view of the stapler design.

FIG. 4 is a left side view of the stapler design.

FIG. 5 is a top view of the stapler design.

FIG. 6 is a bottom view of the stapler design.

FIG. 7 is a front left side perspective view of the stapler design; and,

FIG. 8 is a bottom right side perspective view of the stapler design.

The broken lines in the drawings illustrate portions of the stapler which form no part of the claimed design.
